UNITED STATES PATENT OFFICE.

DOUGLASS M. SMITH, OF WALLA WALLA, WASHINGTON.

TOY GUN.

Application filed December 12, 1925. Serial No. 74,976.

This invention relates to toy guns and has thus forming the trigger aperture 10 simultaneous with the formation of the action slot 9.

5 Another object of the invention is to provide a toy that is exceptionally cheap to manufacture and to assemble.

10 A further object of the invention is to provide a toy gun whose propelling power and projectile is incorporated in one element consisting of a rubber band.

15 A further object of the invention is to provide a toy gun having a method of assembly whereby a report is provided on discharge from an otherwise silent toy.

With these and other objects in view reference is had to the accompanying drawings in which—

20 Fig. 1 is an elevation of the toy in a position ready for discharge;

Fig. 2 is a sectional view of a fragment of the toy;

Fig. 3 is a side elevation of a fragment of the toy;

25 Fig. 4 is a plan view of a fragment of the toy; and

Fig. 5 shows the layout of the action.

Having reference to the drawings like numerals refer to like parts throughout the 30 several views and the numeral 1 refers to the gun which consists of a barrel portion 2, and a grip 3 united to form a stock 4, the barrel portion representing in general outline the barrel of a gun, although the bore is 35 absent, and the grip is provided with a rest 5 extended to form a shoulder 6, that in a general way parallels the line of the butt 7, the two forming a magazine on which the ammunition (not shown) consisting of rubber bands, may be held in reserve.

40 Offset from the shoulder 6 and formed on the rear end of the barrel portion 2 is a breech 8, and the barrel portion and the gun join at the point of the breech and at this 45 juncture form an approximate right-angle with each other to provide for forming an action slot 9, and a trigger aperture 10, in the stock 4.

By this form the slot 9 may be made by 50 one cut of a circular saw, the gun being reversed on the saw table for the purpose and the cut being made by pushing the breech 8 against the saw until the saw passes through the throat 11 of the angle formed by the barrel portion and the grip, as shown in Fig. 2,

thus forming the trigger aperture 10 simultaneous with the formation of the action slot 9. In the action slot is operably mounted a single piece action 12 consisting of a trigger 60 13 and a hammer 14 combined, and which comprise a plate 15, foldable on its central axis (shown by the broken and dotted line in Fig. 5) to provide a smooth trigger face 19 at the bend, and a reinforced, (or doubled) 65 hammer 14 extended to form wings 20, the latter of which are foldable in opposed directions to provide a hammer head 21.

The hammer head 21 is arranged to normally rest adjacent to the breech 8 and joins 70 75 with the front end 22 of the stock 4 to provide a means to maintain a rubber band under tension between the head and the front end, the band being stretched between these two parts.

The action contains a hole 23 through which a pin 24 is driven to form the pivotal point of the action, and the hole is slightly larger than the pin to facilitate assembly.

80 A template (not shown) will be used to locate the pin in the proper position to drive and with the hammer head resting against the breech the action will be located to bring said hole on a proper position with respect to the pin.

To prevent the gun splitting in continuation of the slot 9 a cleat 25 is mounted on the barrel portion and consists preferably of a double pointed tack that spans the said slot, the tack being positioned to receive the shock of the hammer 14 upon discharge.

85 In use a rubber band 26 is stretched over the end 22 of the barrel portion and over the hammer head 21, the latter of which is then pressed down to the normal position 95 of rest adjacent to the breech 8.

100 The tension of the band maintains the action in this position as the head is brought below the pivotal point of said action where it is held by the tension of the band.

Now as pressure is exerted on the trigger 13 the head will raise over the center and be drawn forward to the position shown in Figure 3, when the hammer will strike the cleat and thus provide a quite realistic 105 report.

As the hammer is reinforced by its double thickness there will be little or no wear at its point of contact with the cleat, and while the action may be cast with the reinforced

hammer, the hammer head and the smooth trigger face, yet my preferred form is as described.

Having thus described my invention I 5 claim:

1. In a toy gun, a barrel portion and a grip, united to form a stock, a breech formed on said barrel portion, said barrel portion and grip being arranged to form 10 an angle at their juncture, to provide for forming an action slot and a trigger aperture in said stock with a single cut of a saw and a single piece action mounted in 15 said slot and comprising a plate having wings, and foldable on its central axis to provide a smooth trigger face, and a reinforced hammer, said wings being foldable in opposed directions to provide a hammer head, said hammer head being arranged to 20 normally rest adjacent to said breech.

2. In a toy gun, a barrel portion and a grip, united to form a stock, a breech formed

on said barrel portion, said barrel portion and grip being arranged to form an angle at their juncture, to provide for forming 25 an action slot and a trigger aperture in said stock, a single piece action operably mounted in said slot and comprising a plate having wings, and foldable on its central axis to provide a smooth trigger face and a reinforced hammer, said wings being foldable in opposed directions to provide a hammer head, said hammer head being arranged to normally rest adjacent to said breech, said hammer head forming with the front end 30 of said stock means to maintain a rubber band under tension, and a cleat mounted on said barrel portion and spanning said slot and positioned to receive the shock of 35 said reinforced hammer upon discharge. 40

In testimony whereof I affix my signature.

DOUGLASS M. SMITH.
